UNITED STATES PATENT OFFICE.

JOSEPH STIFTER, OF PITTSBURG, PENNSYLVANIA.

DUMP-WAGON.

No. 878,907.

Specification of Letters Patent.

Patented Feb. 11, 1908.

Application filed August 15, 1907. Serial No. 388,604.

To all whom it may concern:

Be it known that I, JOSEPH STIFTER, a citizen of the United States of America, residing at Pittsburg, in the county of Allegheny and

5 State of Pennsylvania, have invented certain new and useful Improvements in Dump-Wagons, of which the following is a specification, reference being had therein to the accompanying drawing.

10 This invention relates to improvements in dump wagons, and more particularly to that type having hinged bottom doors, commonly known as "drop doors".

15 My invention aims to provide positive and reliable means for holding the hinged doors of a dump wagon in a closed position, especially when a load is carried by the wagon.

20 My invention aims to provide a dump wagon capable of carrying a large load without accidentally discharging the same, a trouble similar to this having been experienced with dump wagons on account of the weak and imperfect locking means used for holding drop doors in closed position. With 25 my wagon I use novel means for closing the drop doors of the wagon and retaining said doors in a closed position, said means being easily and quickly released to precipitate the load carried by the wagon.

30 Further, my invention aims to dispense with the chains and mechanism heretofore employed for elevating the rear ends of drop doors, I having found it only necessary to elevate the front ends and provide means for 35 locking the rear ends, the elevating mechanism besides the locking means being manipulated and controlled from the driver's seat of the wagon.

30 The detail construction entering into my invention will be presently described and then specifically pointed out in the appended claims.

40 In the drawings: Figure 1 is an elevation of my dump wagon, parts thereof being broken away, Fig. 2 is a longitudinal sectional view of the wagon, Fig. 3 is a view of the rear end of the wagon, partly broken away, Fig. 4 is a cross sectional view of the wagon, taken on the line IV—IV of Fig. 2 45 looking in the direction of the arrow of said figure, Fig. 5 is a perspective view of a detached fifth wheel bearing, and Fig. 6 is a perspective view of a detached inverted fifth wheel.

55 My wagon consists of two vertical hopper sides 1 and 2, the forward ends of which are

cut away and supported by the front truck of the wagon, while the rear ends of the hopper sides are supported by a rear truck. The front truck comprises an axle 3, wheels 4, a draft frame 5 strapped to said axle, a fifth wheel bearing 6, and a fifth wheel 7, said fifth wheel being pivotally mounted in the bearing 6 by a bolt 8 and revolubly mounted in a depending frame 9 carried by 60 the forward end of the wagon body. A standard 10 carried by the draft frame 5 and provided with a revoluble roller 11 is used for supporting the depending frame 9 of the wagon. The rear truck comprises an axle 70 12, wheels 14, bolster blocks 15 for the rear seats of the hopper sides 1 and 2, said sides being secured to the bolster blocks 15 and the axle 12 by clefts 16.

Between the hopper sides 1 and 2 is arranged a front inclined wall 17 and a rear inclined wall 18, these walls together with the hopper sides 1 and 2 forming a hopper 19, having its bottom closed by doors 20 and 21, hinged as at 22 to straps 23, secured to the 75 hopper sides 1 and 2. The upper ends of the straps are bent outwardly, as at 24, for supporting inclined side-boards 25 upon the upper edges of the hopper sides 1 and 2. The meeting edges of the hinged doors 20 and 21 are provided with longitudinally disposed angle bars 26 having their forward ends protruding beyond the doors and their rear ends cut away, as at 27, the purpose of 80 which will presently appear.

Journalized in brackets 28 carried by the forward end wall 17 is a shaft 29, said shaft protruding through the hopper side 1 and carrying a ratchet wheel 30 and a pivoted bifurcated lever 31, said lever having a pawl 32 85 pivoted therein for engaging the ratchet wheel 30 and moving the same when the lever 31 is oscillated. The shaft 29 between the bearings 28 is provided with two chains 33, similarly wound upon said shaft. The 90 chains 33 besides being connected to the shaft 29 pass through a strap 34, carried by the forward end wall 17 and are connected as at 35, to the forward ends of the angle bars 26. Through the medium of the lever 31 the 95 doors 20 and 21 are elevated, and to lock the shaft 29 so as to retain the doors in a closed position, the outer face of the hopper side 1 is provided with a pivoted latch 36 having a depending arm 37. The hopper side 1 is also 100 provided with a bracket 38 in which the lever 31 can rest, when the pawl 32 is out of en-

gagement with the ratchet wheel 30 and the lever is not being used.

The rear end wall 18 of the hopper is provided with a bearing 39 and in this bearing 5 and the hopper side 1 is journaled a shaft 40, said shaft having a crank end 41 extending through a link 42, carried by a locking block 43, pivotally carried by two straps 44, secured to the rear axle 12 of the wagon. The 10 outer end of the shaft 40 is provided with a crank arm 45, and pivotally connecting with said arm is a rod 46 extending forwardly along the outer side of the hopper and passing through a keeper 47 carried by one of the 15 straps 23 of the hopper side 1. The rod 46 terminates in an inwardly bent end 48, adapted to engage in the notch 49, formed in the pivoted tread lever 50, said lever being pivotally connected to the inner face 20 of the hopper side 1 by a bolt 51. Arranged between the bolt 51 and the inwardly bent end 48 of the rod 46 is a coil spring 52, the tension of said spring having a tendency to force the rod 46 backward and hold the locking 25 block 46 normally in locking position. The locking block normally engages the cut-away ends 27 of the bars 26, and when said doors are closed, firmly hold the rear ends of said doors and prevent the contents of 30 the hopper 19 from being accidentally discharged. Since considerable pressure will be brought to bear upon the doors 20 and 21 by the load within the hopper 19, it may require considerable force to release the locking 35 block 43, consequently I have provided a pivoted hand lever 53 for engaging the tread lever 50, whereby the driver of the wagon sitting upon the seat 54 can use foot and hand power for moving the rod 46.

40 In order that the forward ends of the doors 20 and 21 will be simultaneously released with the rear ends of the doors, I provide the rod 46 with an upwardly extending lug 55 for engaging the arm 37 of the latch 36, elevating said latch and releasing the shaft 29. The weight of the doors 20 and 21, besides the load which they support will unwind the chains 33 upon the shaft 29.

It is thought that the operation of releasing the doors 20 and 21 and closing the same 50 will be fully understood from the foregoing description, and I reserve the right to make such modifications as are permissible by the appended claims.

55 Having now described my invention what I claim as new, is:—

1. In a dump wagon, the combination with 60 trucks, of hopper sides carried thereby, hopper end walls arranged between said hopper sides, hinged doors carried by said hopper sides, angle bars carried by the confronting edges of said doors, a shaft journaled in 65 bearings carried by one of said walls and protruding through one of said hopper sides, a ratchet wheel carried by said shaft, a bi-

furcated lever loosely mounted upon said shaft and having a pawl to engage said ratchet, chains fastened to said shaft and connecting with the forward ends of said angle bars, a pivoted locking block for engaging 70 the rear ends of said angle bars, a crank shaft carried by one of said hopper end walls for moving said locking block, a rod connecting with said shaft and extending forwardly along one of said hopper sides, a pivoted lever connecting with the forward end of said rod, a latch carried by one of said hopper sides for engaging said ratchet wheel, and a lug carried by said rod for moving said latch and releasing said ratchet wheel. 75

2. In a dumping wagon the combination with a forward and rear truck, hopper sides carried thereby, front and rear end walls carried by said hopper sides, hinged doors carried by said hopper sides, angle bars carried by the meeting edges of said doors, a shaft journaled in bearings carried by said forward end wall, chains connecting with said shaft and with the forward ends of said angle bars, a locking block pivotally supported by 80 said rear truck for engaging the rear ends of said angle bars, a crank shaft for moving said locking-block, a rod connecting with said shaft and extending forwardly at the side of one of the hopper sides, means for winding 85 the first mentioned shaft, and means actuated by the movement of said rod for releasing the first mentioned means. 90

3. A dumping wagon comprising hopper sides, front and rear end walls, doors hinged 100 to said hopper sides, angle bars carried by the meeting edges of said doors, a locking block for engaging the rear ends of said angle bars, a crank shaft for moving said locking block, a rod connecting with said crank 105 shaft and extending forwardly at the side of one of said hopper sides, movable chains connecting with the forward ends of said angle bars, means for moving said chains, and means actuated by the movement of said 110 rod for releasing said shaft.

4. A dumping wagon comprising hopper sides, front and rear end walls, doors hinged to said hopper sides, angle bars carried by the meeting edges of said doors, a locking 115 block for engaging the rear ends of said angle bars, chains connecting with the forward ends of said angle bars, a shaft carried by one of said end walls for winding said chains, a rod arranged at the side of one of said hopper sides for moving said locking block, and means actuated by said rod for releasing 120 said shaft.

5. A dumping wagon comprising a hopper, hinged doors carried thereby, chains connecting with the forward edges of said doors for raising the same, a locking block engaging 125 the rear edges of said doors for holding said doors in a closed position, a rod arranged at one side of said hopper for moving said 130

locking block, means for moving said chains, and means actuated by the movement of said rod for releasing said chains.

6. In a dumping wagon, the combination with a hopper, hinged doors, and means for elevating the forward ends of said doors, of a locking block for engaging the rear ends of said doors, and a rod arranged at the side of

said hopper for releasing said locking block, and the first mentioned means. 10

In testimony whereof I affix my signature in the presence of two witnesses.

JOSEPH STIFTER.
